UNITED STATES PATENT OFFICE.

LUDVIK GÜBA, OF BUBENC, NEAR PRAGUE, CZECHOSLOVAKIA.

MEANS FOR SECURING RAILWAY RAILS.

Application filed October 18, 1924. Serial No. 744,893.

In my United States patent specification No. 1,039,931 a device is described the object of which is to ensure permanently the correct position of railway rails, and which 5 consists essentially in adjusting two clamping members relatively to one another, of which one bears on the rail head and the other on the rail foot and on the means for fastening it to the ties or sleepers. The 10 present invention relates to an improvement on this device, its object being to guard against deformation of the heads of the rail spikes.

According to the invention this object is 15 attained by catching under the head of the rail spike an angle-shaped plate which bears upon the rail foot and upon the tie plate for the rails. This angle-shaped plate, which has holes corresponding to the shanks 20 of the rail spikes, also bears with its inner edge against the clamping stock, so that the latter is likewise secured against lateral displacement.

In the drawing a constructional example 25 of the device is illustrated in section in Figure 1 and in side elevation in Figure 2.

The rail head 1 is held in the correct position by the wedge 3 driven in between its under side and the clamping stock 2. The 30 clamping stock 2 rests with its under surface partly on the head 4 of the rail spike and partly on the rail foot 5.

Under the spike head 4 is caught an angle-shaped plate 6, 7, through the holes in which pass the shanks 8 of the spikes. The 35 plate 6, 7 lies on the tie plate 9 and the rail foot 5, and the upright member 6 supports the head spur 10, while the end of the wide recumbent part 7 extends right up to the 40 wall of the clamping stock 2.

By this means lateral thrusts of the clamping stock against the spikes are nullified.

What I claim is:—

A device for keeping the gage uniform in railway tracks, comprising a rail formed 45 with a rail head and a rail foot, a tie plate whereon said rail foot can rest, a rail spike for securing the rail foot to the tie plate, a clamping stock adapted to rest on the rail foot and on the head of the rail spike, an 50 adjustable strut adapted to rest on said clamping stock and to bear against the under side of the rail head, an angle-shaped plate having a hole through which the shank 55 of the rail spike can pass, said angle-shaped plate being adapted to lie partly on the tie plate and partly on the rail foot, and under the head of the rail spike and to bear against the part of the clamping stock carried by 60 the rail foot to protect the spike from lateral thrusts of the clamp stock.

In testimony whereof I have signed my name to this specification.

LUDVIK GÜBA.
